Primary Examiner — Joseph Kukella*Assistant Examiner* — Lavon M. Amerson(74) *Attorney, Agent, or Firm* — Birch, Stewart, Kolasch & Birch, LLP(57) **CLAIM**

The ornamental design for a head-up display for cars as shown and described.

DESCRIPTION

FIG. 1 is a front, right side, perspective view of a head-up display for cars showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view.

The broken lines indicate portions of the article that form no part of the claimed design. The dot-dash broken lines indicate where the enlargements have been taken, and form no part of the claimed design.

1 Claim, 9 Drawing Sheets(56)
